UNITED STATES PATENT OFFICE.

L ROY PAYNE, OF FRESNO, CALIFORNIA, ASSIGNOR TO SUNLAND SALES COOPERATIVE ASSOCIATION, OF FRESNO, CALIFORNIA, A CORPORATION OF CALIFORNIA.

PAPER-BAG PACKAGE.

Application filed January 20, 1927. Serial No. 164,691.

This invention relates to paper-bag packages of food supplies such as dried fruits, and has as an object the provision of a handy, attractive, and very compact paper-bag sales package of such supplies for the grocer to dispense, as against the weighing out of loose commodities, or the unsightly and unwieldy common paper-bag of such foods, as well as providing a package equal in appearance and compactness to a carton package at lesser cost and one easier to carry.

Briefly described the invention is a combination of a paper-bag package folded in a certain way and engaged by a wire loop handle, and preferably the package having a rectangular form and the handle foldable flat against the package within its contour.

Fig. 1 is a perspective view of the completed package. Fig. 2 is a side elevation of the package with handle folded flat against the top of the bag. Figs. 3, 4, 5, 6, and 7 are reduced size side elevations of the package to illustrate the steps of its making with the aid of a mold, the forward wall of the mold being broken away.

In further detail the paper-bag is designated 1 and the wire handle 2.

The handle 2 engages under a special fold in the end of the bag and is free to swing down from a vertical to a horizontal position as indicated in Fig. 2.

The package tho a paper bag is seen to be of well defined rectangular outline with fairly sharp corners as at A so that when the handle is swung flat against the package as in Fig. 2 it will fall within the outline of the package and the whole will form a rectangular block for packing a number into a shipping case without lost space and so that one will support the other just like carton goods.

The form of the package is due to the nature of its contents (dried fruit) as well as the manner of its making in a mold as shown in Figs. 3, 4, 5, and 6.

To make the package, the bag is placed in a rectangular mold 3 and dried fruit is introduced and forced in tightly with a rectangular plunger 4 to thereby force the fruit into the corners and the bag to assume the exact shape of the mold and make the upper surface of the fruit perfectly flat as indicated by the dotted line 5.

55 The plunger is withdrawn and the bag

folded together over the fruit, to present a vertical quadruple layer central wall 6 as indicated in Fig. 4, after which the extreme end 7 of the bag is folded downwardly against the vertical wall 6, the wire loop handle 2 is placed over the standing fold and the standing fold is then glued or cemented down flat upon the end of the bag as shown in Fig. 6, and the completed package is then removed from the mold.

On account of the pliable and slightly sticky nature of dried fruit such as raisins, prunes, peaches, figs, etc., the rectangular form of the package will endure, in fact will become firmer as the fruit gradually loses some of its moisture in storage.

Instead of the above described method of filling the package the wire loop handle may be secured in place by the same folds described on one end of an empty bag, same as the showing of Fig. 2, and the lower end X of the bag left open for filling. The bag in this case is inverted as it were into the mold with the wire handle 2 at the bottom thereof as shown in Fig. 7, and after which the fruit is forced in the open end of the bag and the same folded and sealed tightly against the surface 5' of the fruit.

In contemplating my package as disclosed in Fig. 1 it will be seen that the flat folding of quadruple wall 6 engaged by the straight aligned ends 2' of the wire handle and with fold 7 cemented down along the upper straight corner A' of the package results in four thicknesses of paper over the handle, thereby removing any danger of the handle tearing out, and the arrangement transmits the weight of the package directly through the entire width of the main vertical walls of the bag to the handle, thus avoiding any tendency of the weight to cause any distortion of the rectangular form of the bag-package.

While I have described the bag as being of paper, and of which material it will usually be made, it is evident that a cloth bag might be formed into the package described and accordingly where I use the words paper-bag in my appended claims I intend this to include any other flexible bag material out of which a package is made in accordance with my invention.

I claim:

1. A bag-package of dried fruit, the fruit presenting a flat upper surface, the bag be-

ing folded upon itself and sealed over the flat surface of the fruit, and a handle engaging under the fold of the bag.

2. A bag-package of dried fruit, the fruit presenting a flat upper surface and vertical flat sides, the bag being folded upon itself and sealed over the flat surface of the fruit along a line adjacent one of said flat sides, and a handle engaging under the fold of the bag.

3. A paper-bag package of dried fruit, the fruit presenting a flat upper surface and vertical flat sides, the bag being folded upon

itself and sealed over the flat surface of the fruit, and a wire loop handle having a leg 15 of the loop extending under the walls of the fold substantially across the bag parallel to said flat sides.

4. A paper-bag with a wire handle secured thereto, said handle being of loop formation 20 with a straight side lying against the bag across the end thereof and the material of the bag being folded to four thicknesses extending over said straight side of the handle and cemented to the body of the bag.

L ROY PAYNE.
